UNITED STATES PATENT OFFICE.

JOHN E. HENDERSON, OF FORT MYERS, FLORIDA, ASSIGNOR OF ONE-HALF TO M. F. JOHNSON, OF FORT MYERS, FLORIDA.

REFRIGERATOR AND DISPENSING DEVICE.

Application filed July 28, 1927. Serial No. 209,077.

This invention relates to a combined refrigerating and dispensing device.

An object of the invention is the provision of a refrigerator in which a plurality of 5 bottled liquids are stored for maintaining the liquids cool and from which the bottles are adapted to be ejected or placed in an accessible position by the insertion of a coin and the manipulation of an operating rod. 10 A further object of the invention is the provision of a refrigerator in which a plurality of bottled liquids are placed in radial relation in a rotatable storage device with mechanism for ejecting the bottles from any 15 one of said devices and for automatically replacing the bottles at the time of the ejection.

A still further object of the invention is the provision of a cooling cabinet and an 20 instrumentality for ejecting bottled liquids from the cabinet, a cooling chamber being located centrally of a circular storage device for the bottles and rotatably supporting said storage device.

25 This invention will be best understood from a consideration of the following detailed description in view of the accompanying drawings forming a part of the specification; nevertheless it is to be understood 30 that the invention is not confined to the disclosure, being susceptible of such changes and modifications which shall define no material departure from the salient features of the invention as expressed in the appended 35 claims.

In the drawings:—

Figure 1 is a front view in elevation of the combined refrigerating and dispensing device,

40 Figure 2 is a fragmentary view in perspective showing the rack for supporting the bottles externally of the refrigerator,

Figure 3 is a view in perspective of a refrigerating chamber,

45 Figure 4 is a side view of the bottle ejecting device,

Figure 5 is a fragmentary vertical section showing the mechanism for discharging the bottles from a rack into the refrigerator,

50 Figure 6 is a view in perspective of the bottle ejecting mechanism,

Figure 7 is a vertical section taken along the line 7—7 of Fig. 1,

Figure 8 is a vertical section through the

refrigerator and ejecting mechanism taken 55 along the line 8—8 of Fig. 7, and

Figure 9 is a horizontal section taken along the line 9—9 of Fig. 7.

Referring more particularly to the drawings 60 10 designates the bottom of the housing for the refrigerator and 11 the back wall which is extended upwardly above the top or cover 12, as shown at 13. A front wall 14 is secured in any approved manner to the side and end walls 15.

65 One of the end walls is provided with an opening which is closed by a hinged door 16 which closes one end of a refrigerating chamber 17. This chamber is supported from the top by means of rods 18 and from 70 the bottom by rods 19, the axis of the chamber is located in line with the axis of the cooling chamber 20 of the refrigerator. On each outer face of the walls of the refrigerating chamber are secured U-shaped brackets 75 21 having rotatably mounted therein grooved walls 22 adapted to receive the inner rim 23 of a rotatable storage device 24.

The bottom of the cooling chamber is provided with a block 25 having a semi-circular 80 face, as shown at 26, slightly spaced from an outer rim 27 of the storage device 24 and upon which the bases of the bottles 28 are adapted to ride when they are being moved to an upright vertical position at the lower 85 end of the rotatable member.

A plurality of rotatable storage devices are located transversely of the cooling chamber 20 and are each located opposite the coin till 29. Above each storage device is located 90 an opening 30 adapted to be normally closed by a pair of doors 31 which are hinged to the top 12 and adapted to be forced open by a bottle which is ejected through the opening 30 in said top. A second opening 95 32 is located in line with the opening 30 and is adapted to be normally closed by a slide 33. Said slide is provided with an opening 34 adapted to be aligned with the opening 32 so that a bottle 28 located within the rack 100 generally designated by the numeral 35 may drop by gravity through the aligned openings 32 and 34 and be received by the rotatable storage device 24.

The slide 33 is guided in its movement by 105 means of a rod 36 located within a slot 37 in the top 12 and reciprocated by means of a manually operated rod 38. The slide also

moves between a pair of brackets 39 secured to the top 12 and upon which is pivotally mounted intermediate its ends a table 40. Links 41 having pivotal connection with the outer end of the table 40 and the slide 33 are adapted to cause rocking of the table so that the outer end 42 is elevated for causing the bottle 28 to be tilted at an angle to the horizontal whereby it will fall by gravity through the aligned slots 32 and 34 and be deposited within a rotatable carrier 24 as will be presently explained.

The rack is formed of a plurality of rods which have horizontal portions 45 at their upper ends and depending vertical portions 46 and 47. The vertical members 47 engage the bottles adjacent their rear ends, while the pair of rods 46 engage the neck and are therefore spaced a less distance apart than the rods 47. One of the rods 46 and the rod 47 are bent to form a sharp angle, as shown at 48, and then upwardly as shown at 49 and then downwardly at 50 adjacent one edge of the table 40, the free end being secured to the top 12 of the refrigerator. The other rods 46 and 47 have an inclined portion 51 adjacent their lower ends upon which the bottles 28 ride and are guided onto the table 40. The lower free ends of the last mentioned rods are secured to the cover 12. The bent portion 49 permits the table 40 to be elevated at the rear end thereof for forcing the bottle 28^a at an angle to the horizontal and away from the adjacent bottom located between the rods 46 and 47. The outer rim 27 of the bottle carrier is provided with a plurality of spaced teeth 60 adapted to be engaged by the flexible member 61 secured to the reciprocating rod 38. This rod is mounted in bearings 62 and 63 carried by brackets 64 extending upwardly from the top wall of the refrigerating chamber 17 and are secured to said wall. As the member 61 engages the teeth and the rod 38 is rotated, the circular storage device will be rotated by a step by step movement. A bell crank lever 70 is pivotally mounted at 71 in the bracket 72 formed integrally with the base member 73 from which rises the brackets 24. One arm 74 of the bell crank lever is provided with a slot 75 to receive a pin 76 secured to the reciprocating rod 38. The other arm 77 of the bell crank lever is also provided with a fork 78 adapted to receive a pin 79 projecting laterally from a sleeve 80 slidably mounted on a square standard 81. The sleeve 80 is provided with a laterally projecting arm 82 having a fork 83 which is adapted to be moved into engagement with the bottle and embraces the lower end of the bottle adjacent the neck as will be presently explained.

A second standard 90 which is square shaped in cross section, is surrounded by a coil spring 91 having one end in engage-

ment with the base member 92 and the other end with a sleeve 93 slidably mounted on the standard 90. An arm 95 projects laterally from the sleeve and has a bottle receiving fork 96 into which the bottle drops after passing through the aligned openings 32 and 34. A pipe 100 extends through the bottom 10, through the block 25 and has its inner open end at a predetermined horizontal level in the cooling chamber 20 so that the water which is melted from the ice located in the refrigerating chamber 17 will be drained off continuously. A second pipe 101 has its outer end closed with a plug 102 and its inner end opening into the chamber 20 at the bottom thereof so that when the plug 102 is removed the water may be drained from the cooling chamber.

The refrigerating chamber 17 has perforations 103 in the bottom wall 104 so that when the ice melts the water will drip through said openings and fall to the bottom of the cooling chamber.

Each till is provided with a coin slot 105 through which the coin is deposited whereby the rod 106 may be released for reciprocation for manually operating the rod 38. The coin controlled mechanism may be of the usual type and is therefore not illustrated. The outer end of the rod 106 projects through the teeth 29 and is provided with a manipulating handle 107.

The operation of my device is as follows:

A coin is dropped into the chute 105 so that when the rod 106 is forced inwardly the coin will release the mechanism for holding the rod to permit reciprocation of the rod 38. As the rod 38 is moved inwardly the flexible member 61 engages a tooth 60 formed on the outer rim 27 causing a predetermined angular rotation of the said ring and likewise the circular storage device. As the rod 38 is moved inwardly the lock which is connected with the slide 33 is moved rearwardly forcing the slide to move likewise, alining the openings 32 and 34. The inward movement of the slide causes the links 41 to move the outer end of the table 40 downwardly and the opposite end is elevated, forcing the bottom 28^a away from the lowermost bottle in the rack 35, this bottle being tilted at an angle to slide off the table 40, falls through the aligned passages 32 and 34 and onto the yoke 96 where the bottle will be supported until the carrier 24 is rotated another step. The spring 91 is compressed when the bottle strikes the yoke 96 by reason of the weight of the bottle and the bottle gently pushed within the cooling chamber.

When the rod 38 is moved inwardly the bell crank lever 70 is rocked causing the sleeve 80 to be moved downwardly on the standard 81 whereby the yoke 83 will engage around the bottle 28 at a point on the bottle adjacent the shoulder between the

neck and the body of the bottle. This downward movement of the sleeve 80 takes place slightly before the carrier has completed its step by step rotation so that the 5 bottle is moved into engagement with the yoke 83.

When the rod 38 is returned to its normal inoperative position the flexible member 61 will drag over the teeth 60 of the 10 rim 27 and will not cause rotation of said rim or the circular storage device. As the rod is reversely actuated the bell crank lever 70 will be reversely rocked causing the arm 77 to be moved upwardly elevating the sleeve 15 80 and the yoke 83 whereby the bottom which is engaged by the yoke will be forced upwardly through the opening 30 and past the doors 31 and projected sufficiently beyond the opening in the doors that it may be 20 grasped by the operator.

During the return of the rod 38 the links 41 are reversely moved whereby the slide 33 is returned to its normal inoperative position, as shown in Fig. 7, whereby said slide 25 will close the opening 32. When the bottle 22 is removed from the opening 30 the doors will fall in place in front of said opening. The table 40 is then returned to its horizontal position whence the lowermost bottle 28 30 in the rack will roll from its position onto the table. Lugs 110 depend from a side edge of the table 40 so that when said table is elevated the lug will be moved into engagement with the bottle indicated by the 35 numeral 111 and prevent said bottle from rolling out of the rack. In other words said lug maintains all the bottles in their normal position until the table is returned.

I claim:—

40 1. In a refrigerator, a cooling chamber, a bottle carrier rotatably mounted in the chamber and provided with a plurality of radially disposed pockets adapted to receive the bottles, manual means for causing rotation of the carrier, means actuated simultaneously with and by the manual means for lifting a bottle from the pocket and ejecting the same from the carrier.

50 2. In a refrigerator, a cooling chamber, a bottle carrier rotatably mounted in the chamber and provided with a plurality of radially disposed pockets adapted to receive the bottles, manual means for causing rotation of the carrier, means actuated by the 55 manual means for lifting a bottle from the pocket and ejecting the same from the carrier, and means actuated by the manual means for causing a supplementary bottle to be moved into the pocket from whence 60 a bottle has been ejected.

65 3. In a refrigerator, a cooling chamber, a bottle carrier rotatably mounted in the chamber, manual means for causing a step by step rotation of the carrier, means actuated by the manual means for ejecting the bottle

from the carrier, a rack supporting a plurality of bottles, and means actuated by the manual means for selectively moving a bottle from the rack and tilting said bottle at an angle to the horizontal whereby said bottle 70 will fall by gravity into the bottle carrier as a replacement for the bottle ejected.

4. In a refrigerator, a cooling chamber, a bottle carrier rotatably mounted in the chamber, manual means for causing a step by step 75 rotation of the carrier, means actuated by the manual means for ejecting the bottle from the carrier, a rack equipped with a plurality of bottles and means adapted to be actuated in advance of the ejecting means for selectively tilting a bottle in the rack at an angle to the horizontal whereby said bottle 80 will slide by gravity into the bottle carrier.

5. In a refrigerator, a cooling chamber, a bottle carrier rotatably mounted in the chamber, manual means for causing a step by step 85 rotation of the carrier, means actuated by the manual means for ejecting the bottle from the carrier, a rack equipped with a plurality of bottles and means adapted to be actuated in advance of the ejecting means for selectively tilting a bottle in the rack at an angle to the horizontal whereby said bottle 90 will slide by gravity into the bottle carrier, spring pressed means adapted to receive the bottle sliding into the carrier and guiding said bottle into the same.

6. In a refrigerator, a cooling chamber, a bottle carrier rotatably mounted in the chamber, manual means for causing a step by 100 step rotation of the carrier, means actuated by the manual means for ejecting the bottle from the carrier, a refrigerating chamber located axially of the bottle carrier and adapted to rotatably support said carrier.

7. In a refrigerator, a cooling chamber, a bottle carrier rotatably mounted in the chamber, manual means for causing a step by step 105 rotation of the carrier, means actuated by the manual means for ejecting the bottle from the carrier, a casing located axially of the bottle carrier and means carried by the casing adapted to rotatably support the carrier, said casing having a refrigerating chamber therein.

8. In a refrigerator, a cooling chamber, a bottle carrier rotatably mounted in the chamber, manual means for causing a step by step rotation of the carrier, means actuated by the manual means for ejecting the bottle from the carrier, said chamber having a curved bottom spaced from the rotatable carrier and adapted to provide a rest upon which the ends of the bottles are seated during part of the rotation of the carrier.

9. In a refrigerator, a housing, a cooling chamber in the housing, a circular bottle carrier rotatably mounted in the chamber, manual means for causing rotation of the carrier, said housing being provided with a 130

top having an opening through which a bottle is adapted to be ejected and a second opening into which supplementary bottles are fed, manual means for causing step by 5 step rotation of the carrier and means actuated by the manual means for ejecting a bottle from the carrier, through the first mentioned opening.

10. In a refrigerator, a housing, a cooling chamber in the housing, a circular bottle carrier rotatably mounted in the chamber, manual means for causing rotation of the carrier, said housing being provided with a top having an opening through which a bottle is adapted to be ejected and a second opening into which supplementary bottles are fed, manual means for causing step by 15 step rotation of the carrier and means actuated by the manual means for ejecting a bottle from the carrier through the first mentioned opening, and means for causing a bottle located exteriorly of the housing to be moved to the second mentioned opening and to be deposited in the rotatable carrier.
20. 11. In a refrigerator, a housing, a cooling chamber in the housing, a circular bottle carrier rotatably mounted in the chamber, manual means for causing rotation of the carrier, said housing being provided with a top having an opening through which a bottle is adapted to be ejected and a second opening into which supplementary bottles are fed, manual means for causing step by 25 step rotation of the carrier and means actuated by the manual means for ejecting a bottle from the carrier through the first mentioned opening, a slide movably mounted on the top of the housing and adapted to normally close the second mentioned opening, means actuated by the manual means for moving the slide away from said opening.
30. 12. In a refrigerator, a housing, a cooling chamber in the housing, a circular bottle carrier rotatably mounted in the chamber, manual means for causing rotation of the carrier, said housing being provided with a top having an opening through which a bottle is adapted to be ejected and a second opening into which supplementary bottles are fed, manual means for causing step by 35 step rotation of the carrier and means actuated by the manual means for ejecting a bottle from the carrier through the first mentioned opening, and means for causing a bottle located exteriorly of the housing to be moved to the second mentioned opening and to be deposited in the rotatable carrier.
40. 13. In a refrigerator, a housing, a cooling chamber in the housing, a circular bottle carrier rotatably mounted in the chamber, manual means for causing rotation of the carrier, said housing being provided with a top having an opening through which a bottle is adapted to be ejected and a second opening into which supplementary bottles are fed, manual means for causing step by 45 step rotation of the carrier and means actuated by the manual means for ejecting a bottle from the carrier, through the first mentioned opening, a slide movably mounted on the top of the housing and adapted to normally close the second mentioned opening, means actuated by the manual means for moving the slide away from said opening, a rack adapted to be supplied with a plurality of supplementary bottles and 50 means actuated by the slide for selectively removing a supplementary bottle from the rack and causing the same to slide through the second mentioned opening and into the bottle carrier.
45. 14. In a refrigerator, a cooling chamber, a circular bottle carrier rotatably mounted in the chamber, manual means for causing a step by step rotation of the carrier, a slidably mounted rod having radially projecting pins, a rockably mounted bell crank lever having its arms provided with yokes, one of said yokes adapted to receive the pin, a standard, a sleeve slidably mounted on the standard having a radially projecting pin and an arm provided with fingers to engage a bottle in the carrier, a lug projecting from the carrier, teeth on said carrier adapted to be engaged by the lug to cause step by step rotation of the carrier, 60 said rod when actuated being adapted to rock the bell crank lever and cause the fingers to move the bottle out of the carrier.

JOHN E. HENDERSON.
